ELEVATING GRADER

Floyd D. Wallace, Indianapolis, Ind., assignor
to J. D. Adams Manufacturing Company, In-
dianapolis, Ind., a Corporation of Indiana

Application March 26, 1932. Serial No. 601,351

7 Claims. (Cl. 37—110)

My invention relates to elevating graders and is particularly concerned with the manner in which the plow-beam of such a grader is mounted.

It is the object of my invention to provide for the plow-beam a mounting which, while capable of adjustment to vary the position of the plow, will nevertheless rigidly hold the plow in any desired position of adjustment. A further object of my invention is to produce a plow-beam mounting 10 through the use of which vertical displacement of the plow owing to irregularities in the surface of the ground over which the grader runs will be lessened. Still another object of my invention is to produce a plow-beam mounting 15 by means of which the plow may be made to cut to greater depth with greater stability than can be secured with prior plow-beam mountings of which I am aware.

In carrying out my invention, I provide the 20 grader with a front axle which is capable of movement relatively to the grader frame in a generally vertical plane. The plow is carried by the plow-beam near one side of the grader frame at a point opposite the belt conveyor on to which 25 it throws the furrow it turns. From the point at which the plow is attached to the plow-beam, the plow-beam extends generally forwardly and inwardly to a point adjacent the center of the front axle of the grader. Instead of connecting 30 the front end of the plow-beam to the grader frame, as has been done in all prior elevating graders of which I am aware, I connect the plow-beam directly to the front axle, preferably close 35 to the point at which draft is applied to the front axle.

The accompanying drawings illustrate my invention: Fig. 1 is a plan view of an elevating grader embodying my invention; Fig. 2 is a detail view illustrating in plan the construction of the 40 front axle which I prefer to employ; Fig. 3 is a front elevation of the grader; Fig. 4 is a side elevation of the grader with parts thereof broken away to illustrate in section some details of the front-axle mounting; and Fig. 5 is an end elevation of the front axle and associated parts.

The grader illustrated in the drawings embodies a generally rectangular main frame 10 supported at one end by front wheels 11 and at the other end by rear wheels 12. Preferably, the 50 front wheels 11 are mounted on steering knuckles 13 which are pivoted on vertical axes to the ends of a front axle 14. The steering knuckles 13 are interconnected by a tie rod 15 to which, near its mid point, there is attached one end of an arm 55 16 which is pivotally mounted on a vertical axis

on the front axle. The front end of the arm 16 is connected to the tongue 17 through which the grader is drawn.

The front axle 14 is preferably connected to the main frame 10 on a horizontal axis in order 60 that it may have a certain amount of generally vertical movement relatively thereto. For this purpose, there is mounted on the front end of the main frame 10 near one side thereof a depending leg 20 to the lower end of which the 65 front axle 14 is pivoted as by means of a pivot bolt 21. The opposite end of the front axle is guided in its vertical movement by being received between two guide bars 22 which depend from the main frame 10. Bumper springs 23 associated 70 with the free end of the front axle 14 and co-operating with an abutment 24 between the guide bars 22 serve to limit vertical movement of the axle.

Those details of the machine which have so far 75 been described form no part of my invention, and may be varied without departing from my invention.

In embodying my invention in a grader of the general type described I mount the plow 25, which 80 is usually in the form of a concave disk, upon a plow-beam 26. The plow-beam is arranged to support the plow near one side of the machine in a position where it will throw earth upon a belt conveyor 27 which extends transversely of the 85 machine and upwardly to an elevated point of discharge. From the point on the plow-beam 26 at which the plow 25 is secured to it, the plow-beam extends generally forwardly and inwardly, terminating at about the middle and in rear of 90 the front axle 14.

As previously indicated, I contemplate that the front end of the plow-beam 26 will be attached directly to the front axle, but the direct attachment of the front end of the plow-beam to the 95 front axle is not essential as it may be otherwise connected to the frame of the machine. For this purpose, I mount on the rear face of the front axle two vertically spaced plates 30 having a series of aligned holes 31. Each pair of aligned 100 holes 31 is adapted to receive a bolt or pin 32 which passes through the eye of an eye-bolt 33 pivotally mounted on an axis longitudinal of itself at the front end of the plow-beam 26.

The lateral reactions at the rear end of the 105 plow-beam 26 are transmitted to the frame of the grader through the medium of a thrust bar 35 which is pivotally connected to the rear end of the plow-beam 26 on a generally vertical axis. From its point of connection at the rear end of 110

the plow-beam the thrust bar 35 extends across the grader frame and at its opposite end is adapted for attachment to the grader frame. Preferably, the end of the thrust bar 35 is provided with a series of spaced holes 36 any of which is adapted to receive a pin 37 mounted in a suitable bracket 38 on the grader frame. The series of holes 36 permit the plow 25 to be adjusted toward or away from the belt conveyor 27 as may be desired. The fit of the pin 37 in the holes 36 is loose enough to permit angular movement of the thrust bar 35 incident to vertical adjustment of the plow.

Vertical adjustment of the plow may be secured 15 by any desired means. In the drawings, I have illustrated this vertical-adjusting means as comprising a chain 40 one end of which is secured to the grader frame 10. The chain passes around a sheave 41 attached to the plow-beam 26 and 20 thence to suitable winding mechanism 42 by means of which the plow-beam and the plow may be raised or lowered as desired.

By the construction described, the resistance of the plow to forward movement is applied directly 25 to the front axle and thence to the tongue, and is not imposed upon the main frame. The mounting of the front-axle in the main frame is thereby freed from large stresses which would otherwise be imposed upon it. In addition, I find 30 that with the plow-beam connected directly to the front axle as above set forth the maximum depth to which the plow can cut before being forced from the ground is materially increased. I believe this latter characteristic to be largely due to 35 the fact that the front end of the plow-beam is held in predetermined vertical position rather than being supported by means which permit it to float vertically under the effect of the varying forces to which the plow is subjected when the 40 machine is in operation, as is the case in most commercial elevating graders of which I am aware.

I claim as my invention:

1. In an elevating grader, a main frame, a front 45 axle mounted for vertical movement relatively thereto, a plow-beam having its front end secured to said axle at an intermediate point thereon, a plow mounted on said plow-beam, and means for adjusting the rear end of said plow-beam vertically, and an adjustable means for 50 positioning said plow-beam laterally of said main frame.
2. In an elevating grader, a main frame, a front axle mounted for vertical movement rela- 55

tively thereto, a plow-beam, means for securing the front end of said plow-beam to said front axle at any of a plurality of points thereon, a plow mounted on said plow-beam, means for adjusting the rear end of said plow-beam vertically, and an adjustable means for positioning said plow-beam laterally of said main frame.

3. In an elevating grader, a main frame, a front axle mounted for vertical movement relatively thereto, a rigid plow-beam having a rear portion extending generally longitudinally of said main frame near one side thereof and a front portion extending forwardly and inwardly to a point adjacent the front axle, means for securing the front end of said plow-beam to said front axle, a plow mounted on the rear portion of said plow-beam, and means for supporting the rear end of said plow-beam from said main frame for lateral and vertical adjustment.

4. In an elevating grader, a main frame, a front axle mounted for vertical movement relatively thereto, a plow-beam having its front end secured to said axle at an intermediate point thereon, a plow mounted on said plow-beam, and adjustable means for positioning the rear end of said plow laterally.

5. In an elevating grader, a main frame, a front axle mounted for vertical movement relatively thereto, a plow-beam having its front end secured to said axle at an intermediate point thereon for vertical and lateral movement, a plow mounted on said plow-beam, and a draft connection attached to said front axle near the point at which the plow-beam is secured thereto.

6. In an elevating grader, a main frame, a front axle mounted for vertical movement relatively thereto, a plow-beam having its front end secured to said axle at an intermediate point thereon for vertical and lateral movement, a plow mounted on said plow-beam, and a draft connection attached to said front axle.

7. In an elevating grader, a main frame, a front axle mounted for vertical movement relatively thereto, a supporting sub-frame having its front end secured to said axle at an intermediate point thereon and its rear end pivotally connected to said main frame, a plow mounted on said sub-frame and located longitudinally of the grader between the points at which the sub-frame is connected respectively to the front axle and main frame, means for adjusting said sub-frame vertically, and an adjustable means for positioning said plow laterally of said main frame.

FLOYD D. WALLACE.

CERTIFICATE OF CORRECTION.

Patent No. 1,924,054.

August 22, 1933.

FLOYD D. WALLACE.

It is hereby certified that error appears in the printed specification of the above numbered patent requiring correction as follows: Page 2, line 100, claim 4, for "plow" read "plow-beam"; and that the said Letters Patent should be read with this correction therein that the same may conform to the record of the case in the Patent Office.

Signed and sealed this 26th day of September, A. D. 1933.
